UNITED STATES PATENT OFFICE.

ROBERT H. KEE, OF LOS ANGELES, CALIFORNIA, ASSIGNOR TO MUN-KEE PRODUCTS CORPORATION, OF LOS ANGELES, CALIFORNIA, A CORPORATION OF CALIFORNIA.

INK PAD AND METHOD OF MAKING THE SAME.

Application filed July 7, 1921. Serial No. 482,875.

To all whom it may concern:

Be it known that I, ROBERT H. KEE, a citizen of the United States, residing at Los Angeles, in the county of Los Angeles and State of California, have invented new and useful Improvements in Ink Pads and Methods of Making the Same, of which the following is a specification.

My invention relates to an improved inking pad and the method of producing the same; the principal objects of my invention being to generally improve upon and simplify the construction of the existing types of inking pads, further to provide an inking pad having two inking surfaces, thereby permitting the pad to be reversed and consequently materially increasing the life or term of service of the pad, further to provide a relatively simple and practical pad that is particularly adapted for use in the resilient stamp pad holder disclosed in the application for patent filed by Whitney K. Munson and myself, April 11, 1921, Serial No. 460, 592, and further to provide a relatively simple and easily practiced method of producing inking pads whereby the cost of manufacture thereof is minimized, and an inking pad having a maximum degree of inking surface is produced.

With the foregoing and other objects in view, my invention consists in certain novel features of construction and arrangement of parts that will be hereinafter more fully described and claimed and illustrated in the accompanying drawings, in which:

Figure 1 is a plan view of an inking pad produced by my improved method.

Fig. 2 is a perspective view of one of the rings or angular members that forms the frame of my improved pad.

Fig. 3 is a perspective view of the companion ring or frame forming member of the pad.

Fig. 4 is an enlarged detail section taken through the edge portion of a pad and showing the parts thereof in the positions occupied prior to the final finishing operation.

Fig. 5 is an enlarged detail section taken approximately on the line 5—5 of Fig. 1.

In the construction of my improved inking pad, and by my improved method of manufacture, a ring or annular frame member 10 is pressed or stamped from sheet metal, and the body of said ring or frame member being substantially L-shape in cross

section and with the horizontally disposed flange 11 inwardly presented.

In the manufacture of this ring or frame member the cutting and stamping operations are performed so as to produce a minute burr 12 on the inner upper edge of the inwardly presented flange 11, and which burr is effective in gripping the fabric covering or facing of the pad and preventing the same from pulling away from the marginal frame of the completed pad.

A companion ring 13 is pressed or stamped from suitable sheet metal, and the body of said companion ring being of inverted L-shape in cross section and with its horizontally disposed flange 14 inwardly presented. In the construction of this companion ring or annular frame member the dies forming the same are manipulated so as to produce a relatively small burr 15 on the lower inner edge of the flange 14, such burr being effective in gripping the corresponding fabric covering of the pad and preventing the same from pulling away from the marginal frame.

The external diameter of the vertical flange of ring 13 is such that said ring fits snugly within the upstanding flange of the ring or frame member 10, and the width of the upstanding flange of ring 13 is substantially less than the width of the upstanding flange of ring 10, so that when the two rings or frame members are properly assembled the upper portion of the vertical flange of ring 10 will project above the top or inwardly presented flange of ring 13. When the two rings or parts of the marginal frame of the pad are properly assembled by being pressed together, the thickness of the finished frame is substantially less than the thickness of the body of the pad (see Fig. 5).

An absorbent portion of the pad comprises a body 16 of suitable fibrous material, the same being interposed between facing members 17 of suitable absorbent flexible material, preferably woven fabric, and this absorbent body is of circular form and of such size as to fit snugly within the frame comprising the rings 10 and 13. In the production of the pad by my improved method, the edge of the absorbent member comprising the absorbent body 16 and facing member 17, is positioned between the horizontally disposed flanges 11 and 14 of the rings or frame members 10 and 13, as illustrated

in Fig. 4, after which the inverted L-shaped ring 13 is forced downwardly within ring or frame member 10 until the lower end of the vertical flange of said member 13 engages the flange 11 of member 10. Inward and downward pressure is now applied to the projecting upper edge of upstanding flange of member 10 so as to bend said projecting edge inwardly and downwardly onto the outer portion of the inwardly projecting flange 14 of member 13, and at the same time pressure is applied to the outer faces of the flanges 11 and 14 so as to bend the same inwardly toward each other and into angular positions with respect to the vertical flanges of the rings or frame members, thereby compressing the edge of the absorbent body of the pad and causing the burrs 12 and 15 on said inwardly projecting flanges to engage in the fabric facings of said absorbent body, with the result that said facings will be effectually prevented from being pulled away from the annular frame of the pad.

25 Thus it will be seen that I have produced a construction utilizing relatively few parts, thereby enabling the pad to be easily and cheaply manufactured, said pad being comparatively light in weight, of substantial structure, provided with a pair of inking surfaces, and the method of producing said pad involving a minimum number of operations that may be easily and quickly accomplished.

35 While I have shown and described a round or circular stamp pad, it will be understood that practically the same method may be employed in producing pads that are substantially oval or rectangular in shape, and that the improved pads may be used in any suitable base or receptacle, although, as above stated, they are particularly designed for use in connection with the base disclosed in the hereinbefore mentioned co-pending application, Serial No. 460,592.

I claim as my invention:

1. In an inking pad, a frame composed of a pair of members that are substantially L-shape in cross section, one member being arranged within the other and with the horizontally disposed flanges of said members inwardly presented, and an absorbent body arranged within said frame with its edges clamped between said inwardly presented flanges.

2. In an inking pad, a frame composed of a pair of members, one of which is dis-

posed within the other, said members being provided with inwardly projecting flanges, an absorbent body disposed within said frame and having its edges clamped between said inwardly presented flanges, and a portion of the outer member of the frame being bent inwardly over the outer portion of the inner frame member.

3. In an inking pad, a frame composed of a pair of members that are substantially L-shape in cross section, one member being arranged within the other and with the horizontally disposed flanges of said members inwardly presented, an absorbent body arranged within said frame with its edges clamped between said inwardly presented flanges, and the inner edges of said inwardly presented flanges being provided with burrs that engage the outer faces of said absorbent body.

4. An inking pad comprising an absorbent body, sections of fabric applied to the faces thereof, a marginal frame for said body of absorbent material and the fabric sections thereon, and the inner edges of which marginal frame are provided with burrs that engage said sections of fabric.

5. An inking pad comprising a body of absorbent material, sections of fabric applied to both faces of said body of absorbent material, and a two part frame clamped upon the edges of said body of absorbent material and the sections of fabric positioned upon the faces thereof.

6. The herein described method of producing inking pads which consists in forming a pair of frame members, one of which is adapted to fit within the other, arranging said frame members upon the edge of an absorbent body, and then simultaneously clamping portions of said frame members upon the edges of said absorbent body, and a portion of one of said frame members upon a portion of the other member.

7. The herein described method of producing inking pads which consists in covering a body of absorbent material with sections of fabric, then applying a pair of cooperating frame members to the edges of said absorbent body of the sections of fabric positioned thereupon, and then applying pressure to said cooperating frame members to clamp the same to each other and to clamp the interposed portions of the absorbent body and sections of fabric thereon.

In testimony whereof I have signed my name to this specification.

ROBERT H. KEE.
